UNITED STATES PATENT OFFICE.

HENRY S. STAUFFER, OF MOUNT JOY, PENNSYLVANIA.

PORCH-IRON.

SPECIFICATION forming part of Letters Patent No. 252,401, dated January 17, 1882.

Application filed November 2, 1881. (No model.)

To all whom it may concern:

Be it known that I, HENRY S. STAUFFER, a citizen of the United States, residing at Mount Joy, in the county of Lancaster and State of Pennsylvania, have invented certain Improvements in Porch-Irons, of which the following is a specification.

My invention relates to porch-irons used as feet or as a base for the posts supporting the roof; and the object of my improvement is to prevent or remedy the sinking of the said posts occasioned by the settlement of the floor upon which the feet rest. To overcome this liability of the posts to sink has always been a source of trouble to builders and house-owners, as it occasions inequalities in the roof of the porch unsightly to the eye and injurious to the structure, in that it is liable to cause openings in the roof and to prevent the proper escape of the water by the pipes. I overcome the difficulty by means of the mechanism illustrated in the accompanying drawings, in which—

Figure 1 is a vertical view of my invention with an arched base; Fig. 2, a vertical view of the same with a socket-base; and Fig. 3 is a vertical section through $x y$ of Fig. 2, showing the manner of fitting the foot of the upright in the socket.

Similar letters refer to similar parts throughout the several views.

The upright U has a screw-thread cut therein, and is supported by a foot or base secured to the porch-floor by means of screws S. When this base is arched, as in Fig. 1, the upright is permanently attached thereto; but when used with a flat base, Fig. 2, it rests in a socket, e, of the same, the socket and end of the upright to fit in it being square, in order to prevent the turning of said upright in operating the nut hereinafter mentioned. Working about this upright screw U is a washer, W, and nut N, cast in one piece, and with a thread cut in

the opening through the center corresponding with the thread of the upright. The upper end of the upright fits freely in a vertical bore, b, 45 of the post D, which bore is of such length as may be necessary.

The porch-irons now in use are of the same general appearance as those illustrated in the accompanying drawings, with this difference. 50 In the old the washer W is cast as a part of the upright U and is located a little above the foot or base, and the upright itself is somewhat shorter and has a perfectly smooth surface. With this iron the sinking of the floor 55 upon which it rests necessitates a like sinking of the post it supports. With my device, the upright being a screw and the washer a nut working about the same, the effect of any sinking of the foundation of the porch-iron upon 60 the post is obviated by screwing up the nut N, with its washer W, enabling the post to be permanently maintained in its normal position.

I have the nut and washer cast in one piece and with the thread cut in the opening through 65 both; but the nut and washer may be cast separately, the nut only having a thread cut through it, and the surface of the opening in the washer working free of the thread of the upright; or, if preferable, the washer may be 70 dispensed with and the post allowed to rest directly upon the nut.

What I claim as my invention, and desire to secure by Letters Patent, is—

In combination with the post of a porch, 75 the upright U, provided with a foot or sleeve adapted to be held fast, the screw-thread cut therein, and a nut, N, with or without a washer, substantially as and for the purpose specified.

H. S. STAUFFER.
